CLAIM

The ornamental design for a game device, as shown and described.

DESCRIPTION

FIG. 1 is a front, right and top perspective view of a game device, showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is a front, right and top perspective view of the game device in use state;
FIG. 10 is a rear, left and bottom perspective view of the game device in use state;
FIG. 11 is a front view of the game device in use state;
FIG. 12 is a rear view of the game device in use state;
FIG. 13 is a left side view of the game device in use state;
FIG. 14 is a right side view of the game device in use state;
FIG. 15 is a top plan view of the game device in use state; and,
FIG. 16 is a bottom plan view of the game device in use state. The broken lines shown in the drawings illustrate portions of the game device that form no part of the claimed design.
